J. N. JACOBS, OF CRITTENDEN, KENTUCKY.

Letters Patent No. 100,412, dated March 1, 1870.

IMPROVEMENT IN CHURNS.

The Schedule referred to in these Letters Patent and making part of the same

To all whom it may concern:

Be it known that I, J. N. JACOBS, of the town of Crittenden, in the county of Grant, and State of Kentucky, have invented certain Improvements in the Construction of Churns; and I do hereby declare that the following is a full, clear, and exact description thereof, reference being had to the accompanying drawings, and to the letters of reference marked thereon.

The nature of my invention consists in constructing the churn in such form, and putting it in motion in such a way as to effect the production of butter from milk and cream, with a large and quick yield of good butter, with ease and cheapness, and without the use of a dash.

To enable others skilled in the art to make and use my churn, I will proceed to describe its construction and operation.

In the drawings—

Figure 1 represents a perspective view of one of the fronts of the churn;

Figure 2, a top view; and

Figure 4, an end view of the top or cover.

A is the body churn, and

B B are the bed-pieces which sustain the frame, composed of the braces D D and the standards O C. These bed-pieces are made of such form, length, and weight as to afford a firm footing for the standard, while the body of the churn is in motion in churning, and the braces are made sufficiently strong to hold the standards firmly in their true positions.

On the top of the body of the churn is fastened a frame, composed of the two arms E E and the round handles F F. These arms may be made fast on the top of the body by vertical bolts passing down through them into it.

The body of the churn is suspended between the standards by metallic bolts passing through the standards near their tops, as shown in fig. 2, from their outsides, and through the upper ends of metallic plates or lugs, d d, made fast to the arms by screw-bolts or otherwise, so that the bearing-bolts will be above the arms E E. These bolts are not turned in the standards, but are fixed fast in them, and the body of the churn, by means of the lugs or plates d d, swings upon them.

By this mode of suspension, the scope of motion of the body of the churn has been made as great as is deemed practicable.

In one side of the body of the churn is made a circular opening for the discharge of the butter-milk, or of water when the churn is to be washed.

The interior of the body may be lined with tin or any other suitable metal, and the exterior may be covered with like material.

The metallic covering on the outside of the body

may have soldered upon it a discharge-pipe, over the opening before mentioned, and this pipe may be formed of any suitable metal, and formed with a male screw upon the outside of it, upon which a cap of similar metal, with a female screw in its interior, may be fitted, so that the opening may be tightly closed by screwing on such cap.

The cap in the drawings is marked c'.

The opening in the top of the body is closed by the cover shown in fig. 4, so as to prevent the escape of the milk while churning, but to allow a circulation of air.

The flanges of the cover n n by extending over the lips of the opening prevent the escape of the milk.

The cover should have an opening for an air-hole through its center; but to prevent the escape of milk while the churn is in motion, I place and fasten over the hole an oblong cover, made of tin or other suitable metal, in the form of the half of a hollow cylinder, extending nearly from one end of the cover to the other, and have a circular hole in each end, for the admission and emission of air into and out of the churn through the hole in the cover above described. By means of the cover so constructed, air may pass into and out of the churn while in motion, but milk cannot.

The metallic piece a may be fastened upon the cover as shown in the drawings, or otherwise.

Having thus given a general view of the construction of the whole churn, I will now proceed to give a more particular description of the peculiar form of the body of my churn, and the effects caused by such peculiar form.

By reference to the end view presented in fig. 2, it will be seen that the lower part of each head-piece, from e down under the bottom and up to e again on the other side, is in form of a half circle, and that from the points e on each side up to f on each side, the walls are suddenly drawn in, but from the points f f the walls extend upward in lines nearly straight, until they reach the top, with which they make angles of about thirty degrees.

In churning, the churn is to be worked by the handles F F, which may be raised and depressed alternately, with such speed of motion as will secure the greatest agitation of the milk.

By the motion so given to the cream or milk in the body of the churn, it is made to flow in currents, with violence, back and forth, and the walls, from e on each side of the top, are made to strike the currents square on the head and break them into spray, and thus effectually break the oily globules of the cream and form butter; and in this process the air is made to assist the walls of the churn in making that thorough division and subdivision of the cream which is so necessary in the process of churning for butter.

It is scarcely necessary to remark that, as my churn has no dash or other work or device in its interior, it is easily kept clean and dry when not in use, the butter is easily removed from it, and, moreover, it is so simply and so easily operated that the strength and intelligence of a child are sufficient for it, and its construction is so simple that any mechanic, with aid of a few tools, can make one.

What I claim as new, and desire to secure by Letters Patent, is—

1. The churn-body A, when constructed without a dash or other interior device, with the lower part nearly in the form of a half cylinder, and from the shoulders

ee on either side, extending up to the top on each side in lines nearly straight, substantially as and for the purpose described.

2. The top or cover, when constructed substantially in the form and for the purposes described, in combination with the elements of the first claim.

3. The several parts of the churn, arranged and operated as described, as a whole, substantially as set forth.

J. N. JACOBS.
